United States Patent Office.

SAMUEL B. JEROME, OF NEW HAVEN, CONNECTICUT, ASSIGNOR TO SAMUEL PECK & CO., OF SAME PLACE.

Design No. 4,422, dated October 18, 1870.

DESIGN FOR A CLOCK-CASE SASH.

The Schedule referred to in these Letters Patent and making part of the same.

To whom it may concern:

Be it known that I, SAMUEL B. JEROME, of the city and county of New Haven and State of Connecticut, have invented a new and original Design for the Fronts or Sashes of Clock-Cases, of which the following is a specification, reference being had to the accompanying drawing.

The design herein represented is intended for the door or sash of a clock-case.

It consists of a frame having parallel sides, and a bottom at right angles with the sides.

The top of the frame is made pointed, its outline being made up of the two lines a^1 a^1 , which, when taken in connection with a line drawn between the upper ends of the sides and parallel with the base of the frame, will form an isosceles triangle.

With these two sides a^1 a^1 as a basis, I trace on the clock-frame a hexagonal figure as represented in the

drawing, the two intermediate sides, a a , being formed by the sides of the frame, and the two lower sides, a^2 a^2 , corresponding to the upper sides a^1 a^1 , meeting at a point diametrically opposite the point where the upper sides meet.

This portion of the clock-sash constitutes the molding or raised portion, which is intended to surround the clock-dial.

Below the hexagonal molding there is a rectangular panel or molding, b , as shown in the drawing.

What I claim, and desire to secure by Letters Patent, is—

The design for the front or sash of a clock-case, as herein represented.

SAMUEL B. JEROME.
